UNITED STATES PATENT OFFICE.

THEODORE J. STEEN, OF ST. PAUL, NEBRASKA.

WASHING-MACHINE.

SPECIFICATION forming part of Letters Patent No. 767,969, dated August 16, 1904.

Application filed May 2, 1903. Serial No. 155,349. (No model.)

To all whom it may concern:

Be it known that I, THEODORE J. STEEN, a citizen of the United States, residing at St. Paul, in the county of Howard and State of Nebraska, have invented new and useful Improvements in Washing-Machines, of which the following is a specification.

This invention relates to washing-machines; and the object of the same is to provide means whereby the washing operation may be more expeditiously carried on by holding the articles of clothing positively applied to a rotatable drum through which the water or suds is permitted to freely pass and contact with the clothes.

The invention consists in the construction and arrangement of the several parts, which will be more fully hereinafter described and claimed.

In the drawings, Figure 1 is a perspective view of a washing-machine embodying the features of the invention. Fig. 2 is a transverse vertical section on the line 2 2, Fig. 1. Fig. 3 is a longitudinal vertical section on the line 3 3, Fig. 2, showing the cover, which carries the washing-drum, thrown backwardly in dotted lines. Fig. 4 is a longitudinal vertical section on the line 4 4, Fig. 2, through the cover, taken in a plane to one side of that shown by Fig. 3.

Similar numerals of reference are employed to indicate corresponding parts in the several views.

The numeral 1 designates a suds box or casing, which may be constructed of suitable material, preferably galvanized sheet-iron, and has at one end, below the upper edge thereof, a ledge 2. The box or casing 1, as shown, is rectangular; but other contours may be adopted at will.

To the box or casing 1 a cover 3 is hinged through the medium of straps 4, secured to the opposite sides of the box near the end distant from that having the ledge 2, the said straps extending upwardly above the upper edge of the box and pivotally connected to the opposite sides of the cover. The cover 3 is of less length than the box or casing 1, and the lower edge of the free end thereof is adapted to rest on the ledge 2, as clearly shown by

Fig. 3, and leave a space for the application of a wringer which is partially supported by the said ledge.

The working parts of the washing-machine are carried by the cover 3 and comprise a drum having opposite sheet-metal heads 5 and a circularly-disposed reticulated periphery 6, the closure having less diameter than the heads 5. By making the heads 5 of greater diameter than the periphery 6 a seat is formed for holding the clothes in close contact with the said periphery 6, and the clothes are also thus prevented from falling over against the outer surfaces of the heads, with the material advantage of being more effectively cleansed during the operation of the machine. The heads 5 have openings 7 therein, one in each, to permit the water or suds to flow therethrough into the interior of the periphery 6, and regularly disposed in and movable through the periphery 6 are clamping loops or holders 8, having bars 9, normally held against the exterior of the closure, and inner centrally-bent connecting-bars 10, from which coil-springs 11 extend to oppositely-disposed similar connecting-bars throughout the series of clamps or holders. The springs 11 are arranged in diametrical planes, and each spring connects two clamps or holders, as clearly shown by Fig. 3. The function of the clamps or holders is to secure the articles of clothing against the exterior surface of the periphery 6, so that the water passing through the heads 5 may be brought more reliably in contact with the articles of clothing on the closure. The drum is rotatably held on stub-shafts 11^a, projecting inwardly from the lower portions of the opposite sides of the cover, as clearly shown by Fig. 2, and on one of said stub-shafts is an operating-pinion 12, held in continual mesh with a drive-pinion 13, secured to the drive-shaft 14, having an operating-handle 15 on the exterior of the machine, the pinions 12 and 13 being inclosed by a box or casing 16 for obvious reasons. The rotation of the drum within the suds-box and cover after articles of clothing have been secured thereto by the clamps or holders and a suitable quantity of suds or water poured into the box or casing will effect a thorough clean-

ing treatment of the articles of clothing; but to render such operation more effective and expeditious a small drum 17 is movably held in the upper part of the cover by a pivoted hanger 18, having its ends inturned and passed through opposite heads of the drum 17. The said drum 17 constitutes what may be termed a "rubber" and is held down in firm contact with the periphery 6 by a spring 19, caught over one of the side arms of the hanger at its upper end and adjustably looped around a holding-bar 20 in the interior of the cover adjacent to one side of the latter. The bar 20 has notches 21 in its lower edge to receive the terminal loop or hook at the lower end of the spring 19, and for convenience in adjusting said spring the lower terminal thereof is provided with a ring 22. It will be seen that the tension on the rubber may be quickly regulated to decrease or increase the same by shifting the lower end of the spring inwardly and outwardly in relation to the bar 20. As the drum carrying the clothes is rotated the rubber revolves thereover in close contact therewith.

The improved machine will be found exceptionally useful for the purpose for which it has been devised, and changes in the proportions, dimensions, and minor details may be resorted to without in the least departing from the spirit of the invention.

Having thus fully described the invention, what is claimed as new is—

1. A washing-machine, having a rotatable cylinder with a reticulated periphery and ends projected beyond the periphery in the form of flanges to hold the clothes in close engagement with the said periphery, transversely-extending clamping-loops having their outer bars resting on the reticulated periphery and also provided with side portions movable through the said periphery and connected to each other within the body of the cylinder, and a series of springs having their opposite terminals attached to the inwardly-projecting portions of oppositely-disposed pairs of clamping-loops, each pair of

loops having the terminals of one spring attached thereto and all the springs loosely crossing each other at angles and in unattached relation within the center of the cylinder.

2. A washing-machine, having a rotatable clothes-drum with a reticulated periphery and substantially closed ends with flanges projecting outwardly beyond the periphery to provide means for retaining the clothes in contact with said periphery, and clothes-clamping loops having outer bars extending transversely over the exterior of the periphery, and sides freely movable through said periphery, the sides of each loop being connected within the body of the drum, and spring devices attached to the centers of the connected portions of the loops within the drum, said spring devices being so arranged in relation to the pairs of clamping-loops that the latter will operate against each other.

3. A washing-machine having a rotatable clothes-drum with a reticulated periphery and ends having flanges projecting outwardly beyond the periphery to provide side guards, means for clamping the clothes on the reticulated periphery, a roller pivotally supported and adjustably disposed over the top portion of the drum and held between the flanges in contact with the said periphery, a removable cover in the upper part of which said roller is mounted, a horizontally-disposed holding-bar in the lower part of the cover, said bar being provided with notches in the under edge thereof, and a spring having its upper end engaging a part of the support for the roller, and its lower end loosely and movably engaging the bar, the tension of the spring and the roller being varied by moving the lower end of said spring into engagement with the various notches in said bar.

In testimony whereof I affix my signature in presence of two witnesses.

THEODORE J. STEEN.
